US00D621392S

(12) **United States Design Patent**
Matsuoka

(10) **Patent No.:** **US D621,392 S**
(45) **Date of Patent:** ** *Aug. 10, 2010

(54) **MOBILE COMPUTING DEVICE HAVING A NAVIGATION BUTTON COMBINATION**

D344,523 S * 2/1994 Kanno D14/218
D346,797 S * 5/1994 Tokiyama D14/138

(75) Inventor: **Yoshimichi Matsuoka**, Cupertino, CA (US)

(Continued)

(73) Assignee: **Palm, Inc.**, Sunnyvale, CA (US)

FOREIGN PATENT DOCUMENTS

(**) Term: **14 Years**

WO DM/050409 * 3/1999

(21) Appl. No.: **29/277,535**

(22) Filed: **Feb. 28, 2007**

(57) **CLAIM**

The ornamental design for a mobile computing device having a navigation button combination, as shown and described.

DESCRIPTION

FIG. 1 is a frontal view of a mobile computing device having a navigation button combination;

FIG. 2 is a first isometric view of FIG. 1; and,

FIG. 3 is a second isometric view of FIG. 1.

The broken line showing of the inner portion of the elongated oval border of the navigation button represents a boundary within the claimed design while the broken line showing of the inner portion of the display and all other broken lines are directed to environment; the broken lines form no part of the claimed design.

1 Claim, 3 Drawing Sheets
